ARTHUR R. MEYER AND ELMER A. REED, OF CHICAGO, ILLINOIS, ASSIGNEES, BY
MESNE ASSIGNMENTS, TO WILSON-JONES LOOSE LEAF COMPANY, OF CHICAGO,
ILLINOIS, A CORPORATION OF MASSACHUSETTS.

MECHANISM FOR SHIFTING BINDER POSTS.

Application filed June 18, 1921. Serial No. 478,491.

To all whom it may concern:

Be it known that we, ARTHUR R. MEYER and ELMER A. REED, citizens of the United States, and residents of the city of Chicago, 5 in the county of Cook and State of Illinois, have invented certain new and useful Improvements in a Mechanism for Shifting Binder Posts; and we do hereby declare that the following is a full, clear, and exact description of the same, reference being had to the accompanying drawings, and to the numerals of reference marked thereon, which form a part of this specification.

Our invention relates to loose leaf binders 15 in which leaves or pages can be readily inserted and removed; and in which the said leaves are adapted to be locked by shiftable posts as set forth in our copending application Serial No. 478,488, of which the device 20 in this application represents an improvement.

It is an object of this invention to provide a practical and simple mechanism whereby the shiftable parts for locking and unlocking the leaves of the binder may be readily operated.

With these and other objects in view which will become apparent in the following description and disclosures, our invention 30 comprises the novel features of construction hereinafter described and more specifically defined in the appended claims.

In the accompanying drawings which illustrate a preferred embodiment of our 35 invention and in which similar reference characters refer to similar features in the different views:

Figure 1 is a front plan view of our improved binder showing the posts and actuating mechanism interiorly thereof.

Figure 2 is a section on line 2—2 of Figure 1, with a part of the cover omitted.

Figure 3 is an outer elevational view of the lower side plate taken substantially on 45 line 3—3 of Figure 4.

Figure 4 is a section on the line 4—4 of Figure 1.

Figure 5 is a fragmentary section taken on the line 5—5 of Figure 1.

Figure 6 is a section through the binder showing the post-actuating means and the manner of securing the leaves in the binder.

Figure 7 is a plan view of the type of leaf adapted to be used in the binder.

Figure 8 is a fragmentary section on the 55 line 8—8 of Figure 4.

As shown on the drawings:

The binder to which our invention is applied comprises a pair of side walls 1 each having an inwardly directed flange 1^a at 60 right angles thereto which slidably rests upon the back or base plate 2 which is bent or crimped at its ends over the ends of said flanges to sheathe the same as shown in Figure 1. The covers 3 are hinged to the upper 65 ends of the side walls 1, and these walls 1 and covers are movable toward and from each other by means of a screw member 4 extending longitudinally of the binder and anchored to the back plate 2 by means of 70 bearing brackets 5, and having reversely threaded sections upon which nuts or shiftable elements 6 are adjustable. A pair of links 7 are pivotally connected to each nut 6 and extend in divergent relation to the 75 side walls 1 to which they are attached, so that upon rotation of the screw 4 the side walls 1 are moved either apart to open the binder, or together to close the binder.

The leaves of the binder are retained in 80 place by means of a plurality of relatively slidable posts 8 and 9 which in the present instance telescope one within the other. These posts are mounted upon plate members 10 which are in turn slidably supported 85 upon the side walls 1 of the binder at the proper heights. Each plate member 10 is slidably supported on an inner wall 1 of the binder by means of a plurality of headed projections or studs 11 projecting therefrom 90 and extending through slots 12 in said side walls with the heads on the studs in slidable engagement with the outer surface of said wall and overlapping said slots. The length of these slots may govern the length of 95 longitudinal movement of the plate members 10 and hence that of the posts carried thereby, if desirable. This structure, however, forms no part of our present invention except in so far as it is modified or co-acts 100 with our present invention, since the same is described and claimed in our copending application.

This invention relates more directly to means for shifting or operating the plate members 10, and contemplates mechanism for simultaneously shifting all the plate members at a single operation for locking 105

or unlocking the sheets in the binder. For this purpose, the slidable plate members 10 are connected to shiftable elements which are simultaneously shifted in opposite directions by the adjustment of a single member. In the present instance, we have utilized the longitudinal shiftable nuts 6 as the shiftable elements and the screw member 4 as the single member which can be adjusted by rotating the same for shifting the nuts 6 in either direction. The plate members 10 may be variously connected to the screw member 4. A preferable arrangement, however, consists in using four plate members 10 and 15 connecting each one to a link member 7. Accordingly, the two plate members 10 connected to one nut or shiftable element 6 will be shifted as a pair in one direction, while the two plate members 10 connected to the other nut or shiftable elements 6 will be shifted as a pair in the opposite direction upon the operation of the screw member 4.

One method of connecting the plate members 10 to the links 7 has been illustrated. 20 As shown in Figures 2 and 4, each plate member is provided with a downwardly extending leg having an integral lug 13 that is connected by a bolt or rivet 14 with a link 7, and to prevent the downwardly extending leg portion from being bent inwardly or distorted when the sides of the binder are brought together in the act of closing the same and also for properly limiting the movements of the posts and providing a sliding hinge or lost motion connection, a 25 bracket 16 of angle shape having a horizontal slotted flange and a vertical flange is provided to slidably anchor each plate member 10 to the side walls 1. The vertical flanges of said brackets lie closely adjacent the outer surface of the side walls; the horizontal flanges extending through slots in said side walls in position to have the bolts 14 operable in the slots thereof as 30 shown in Figures 1, 3 and 4. The slots in the horizontal flanges of the brackets 16 should be equal to the length of the movement of the slidable plates 10 and limit the movement thereof at the locking and unlocking position of the posts.

As previously pointed out, the plate members 10 are connected to move in pairs in opposite directions, and each such pair supports one or more pairs of relatively slid- 35 able posts 8 and 9. In the present instance, each pair of plate members supports two pairs of posts for cooperating with suitably formed slots such as the mushroom or T-shaped slots in the loose leaves illustrated in Figures 6 and 7.

The operation is as follows:

Assuming that the binder is open and that the posts are in unlocking position as shown in full lines in Figure 6 in which position it is obvious that a leaf may be removed or in-

serted. When it is desired to lock the leaves in the binder, it is only necessary to apply a key to the polygonal end 17 of the screw element 4 and turn the same in the proper direction to move the nuts or shiftable members 6 toward each other. This operation will move the posts which are connected to said nuts into the longitudinal portions of the slots as shown in dotted lines in Figure 6 and securely lock the leaves against transverse or longitudinal movement. When the bolts or rivets 14 reach the inner ends of the respective slots in the brackets 16, the said posts will be in locking position with respect to the slots in the loose leaves. Further movement of the shiftable elements in the same direction will then draw the sides of the binder toward each other as far as the telescopic posts or the number of leaves will allow to close the binder. In unlocking 85 the binder the screw element 4 is turned in the opposite direction to shift the nuts 6 outwardly. This operation will shift the bolts or rivets 14 in their slots to the outer ends of said slots to bring the leaf-holding means or 90 posts into the entrance necks of the slots in the loose leaves to unlock the same. Further movement in the same direction will then completely expand the sides of the binder. Thus the first part of the operation 95 in closing the binder will bring the posts to leaf-locking position while the first part of the operation in opening the binder will bring the posts to leaf-unlocking position. This operation arises from the fact that far 100 less force is required to shift the plate members 10 than is required to expand or contract the binder, and further from the fact that the horizontal component of force acting on the plates 10 is much greater than the 105 transverse force acting to contract or expand the binder; therefore causing the bolts or rivets 14 to first traverse the length of the slots in the brackets 16 for locking or unlocking the leaves before the transverse 110 component of force will come into play for contracting or expanding the sides of the binder.

When the leaves of the binder are in unlocked position, they can be readily offset 115 just as described in our copending application, and the binder is adopted for both pen and ink and mechanical bookkeeping.

From the foregoing, it will be apparent that we have invented a simple and practical 120 mechanism for simultaneously shifting a plurality of posts in opposite directions for locking or unlocking the loose leaves in a binder and also expanding or contracting the binding mechanism.

We are aware that numerous details of construction may be varied through a wide range without departing from the principles of this invention, and we therefore do not 125 purpose limiting the patent granted there-

on otherwise than necessitated by the prior art.

We claim as our invention:

1. In a loose leaf binder, a plurality of pairs of slidable plate members, leaf-holding posts carried by said members, a longitudinal screw member rotatably anchored in the binder and having a plurality of reversely threaded sections, shiftable elements on said threaded sections, and means connecting said slidable plate members to said shiftable elements.
2. In a loose leaf binder having a plurality of slidably supported plate members and leaf-holding posts carried by said members, a screw member having reversely threaded sections rotatably anchored in said binder, shiftable elements on said threaded sections, links connecting said slidable plate members and shiftable elements, and brackets slidably anchoring said links to the sides of said binder.
3. In a loose leaf binder, the combination with the shiftable elements for expanding and contracting the binder, of shiftable leaf-holding posts operatively connected to said elements, a loose leaf having a plurality of mushroom-shaped slots for accommodating the leaf-holding posts and allowing said posts to be shifted therein for locking said leaf in the binder.
4. In a loose leaf binder, two pairs of slidably supported plate members, leaf-holding posts carried thereby, a screw-threaded element having reversely threaded portions, nuts on said reversely threaded portions, links connecting said slidable members and nuts, and a slotted connection between said links and the sides of the binder.
5. In a loose leaf binder, expandable side members, longitudinally slidable plates supported on said side members, leaf-holding means supported by said plates, a screw element having reversely threaded sections, nuts on said threaded sections and means connecting said nuts and plates and operable for shifting said plates in advance of expanding said sides.
6. In a loose leaf binder, expandable and contractable side members, mechanism for contracting and expanding said sides, slidable plates carried by said sides, leaf holding posts carried by said plates, said plates being connected to said mechanism for shifting movements in advance of the contracting or expanding movements of the side members.
7. In a loose leaf binder, expandable and contractable side members, plates slidably supported on said sides, leaf-holding posts rigidly supported on said plates, shiftable elements, a device for simultaneously shifting said elements and means connecting said plates and shiftable elements for successively shifting the said plates and contracting or expanding said side members.
8. In a loose leaf binder, side members, a plurality of pairs of plates slidably supported on said members, a leaf-holding post carried by each pair of members, a plurality of shiftable elements, a device for simultaneously shifting said elements, and a plurality of pairs of links, each pair connecting a pair of plate members with a shiftable element.
9. In a loose leaf binder, a back, expandable and contractable side members, two pairs of parallel plates slidably supported by said sides and having downwardly extending legs with integral lugs at right angles to said legs, a screw shaft rotatably anchored in the back of the binder and having reversely threaded sections, nuts on said threaded sections, links connecting said lugs and nuts, and brackets secured to the sides of the binder and having slotted lugs superposed on the other lugs for receiving the link-connecting means.
10. In a loose leaf binder, a back, expandable and contractable side members, a shaft having reversely threaded sections anchored in the back of the binder, nuts on said threaded sections, longitudinally shiftable leaf-holding posts carried by said members, means connecting said posts and nuts, and a lost-motion connection, between said means and the sides of the binder.
11. In a loose leaf binder, expandable and contractable side members, slidable plates carried thereby, leaf-holding means carried by said plates, shiftable elements, means for simultaneously shifting said elements, links connecting said plates and elements and slotted brackets connecting said links with the sides of the binder for the purpose set forth.

In testimony whereof we have hereunto subscribed our names in the presence of two subscribing witnesses:
